ARTICLE OF FURNITURE

Sylvia D. Epworth, New York, N. Y., assignor to
 George Spalt & Sons, Inc., Albany, N. Y., a corporation of New York

Application April 8, 1944, Serial No. 530,194

5 Claims. (Cl. 311—1)

This invention relates to articles of furniture, and relates more particularly to tables, or the like, provided with a removable plug which may be disposed in the center of the table, or at any other convenient point.

In end tables, center tables, bridge tables, or the like, it is frequently desired to place a lamp in the center or at some other convenient point on the table, and in cases particularly where it is desired to place the lamp in the center, there is always the objection of the lamp cord extending over the surface of the table to the edge thereof. It is an object of the present invention to provide a table of special construction having a small opening therein within which is fitted a removable plug.

When a lamp is to be placed on the table, the plug is conveniently removed, thus permitting the lamp cord to pass through the opening to the lower surface of the table top, and thence to the base receptacle. When the lamp is removed from the table and the plug inserted in place within the opening, the upper surface of such plug is flush with the upper surface of the table top, and the plug has a sufficiently snug fit to cause it to appear as an inlaid element. Novel means are positioned on the lower surface of the table top to retain the plug in this latter position, and when it is desired to remove the plug, this retaining element, which is pivotally mounted on such lower surface of the table top, also is formed with a recess which supports the plug in this inoperative position, thus eliminating the possibility of the plug being lost during its period of non-use.

It is accordingly one of the principal objects of the present invention to provide a table of the character described having the removable plug which is readily inserted within the table top opening, and may also be removed with equal speed and facility. Another object of the present invention is to provide a table or similar article of furniture with a central or otherwise shaped opening, provided with a removable closure element, which greatly increases the usefulness of the table, and may be added as an element thereto with only very slight additional cost.

In the drawing:

Fig. 1 is a plan view of a table embodying the present invention.

Fig. 2 is a vertical section taken on line 2—2 of Fig. 1.

Fig. 3 is a broken bottom plan view of a table top embodying the present invention.

Fig. 4 is a broken vertical section showing a modified form of the invention.

Fig. 5 is a bottom plan view thereof.

The table includes a table top 10 of any desired size or shape, and a plurality of legs 11. At the center, or any other desired point on the table top, 5 a circular or other shaped opening 12 is provided, such opening preferably having an enlarged portion 13 at its lower end, thus forming a shoulder 14. The plug 16 is formed with an external periphery of such size as to relatively snugly fit opening 12, but the fit should not be so tight as to prevent the plug from being readily removed from the opening. The plug is further formed with an annular flange 17 at its lower end, the collar 18 formed by such flange being seated against shoulder 14, thus limiting upward movement. The plug is so proportioned as to cause its upper surface to be planar with the upper surface of the table top when in the position illustrated in Fig. 2. The outer periphery of the flange 17 is of such size as to fairly snugly fit the enlarged portion 13 of opening 12.

The retaining element for the plug may comprise a block 20 which may be generally rectangular in shape, although it may, if desired, be rounded at one end, as shown at 21. It is pivotally secured to the lower surface of the table top by means of a screw 22, or by any other suitable means. On its lower surface, retaining block 20 carries a plug support 24 formed with a slot 25 extending inwardly from one end thereof of sufficient width to receive plug 16. Slot 25 is further formed at its upper end with an enlarged portion 26 of sufficient width to receive flange 17 of plug 16.

35 It will accordingly be seen that when plug 16 is inserted within opening 12 in the table top, as shown in Figs. 1 and 2, it is supported in this position by retaining block 20. When, however, it is desired to remove the plug for the purpose of receiving the light cord through opening 12, block 20 is merely swung to one side, as illustrated in the broken lines in Fig. 3, thus permitting the plug to be moved downwardly and out of the opening in the table top. Retaining block 20 40 may thus be left in this position to one side of opening 12, and the plug 16 turned upside down and inserted within slot 25 wherein flange 17 is supported in the enlarged portion 26 of such slot. It is shown in this position in broken lines in 45 Fig. 2.

In the modified form of the invention illustrated in Figs. 4 and 5, the table top 10 is provided with the opening 12 having the enlarged portion 13 at its lower end, and plug 16 having flange 17 at its lower end is received within the

opening in the same manner as in the first embodiment of the invention. In this instance, however, the combined plug retaining and supporting element 30 may be generally sector-shaped, and is also pivotally secured to the lower surface of the table top by means of screw 31. The block 30 is sufficiently wide at its end opposite pivot 31 to provide a plane surface 32 for supporting plug 16 when the same is inserted in place within the table top, as shown in Fig. 4.

The approximate position of the lower surface of the plug relative to retaining block 30 is illustrated in broken lines 33 in Fig. 5. The retaining block is further formed with an opening 34 of slightly larger diameter than the greatest diameter of the plug 16, such opening extending from the upper surface of such block to a point spaced from the lower surface thereof, thus forming a lower supporting wall 35 for the plug. This wall may have a central aperture 36.

When it is desired to remove the plug from the opening in the table top, the supporting block 30 is swung to one side, to a point wherein opening 34 registers with opening 12-13 in the table top, and when in this position, the plug is forced downwardly and is accordingly received within recess 34, and rests upon lower wall 35. The supporting block is now rotated somewhat further on its pivotal support, and the cord may then be run through the opening 12. When it is desired to return the plug to its position in the table top, the supporting block 30 is merely rotated to the second-mentioned position, that is, wherein opening 34 registers with opening 13, and the plug moved upwardly by inserting one's finger through opening 36, after which block 30 is rotated to the first-mentioned position.

While I have herein shown and described two forms or embodiments of my invention for illustrative purposes, and have disclosed and discussed in detail the construction and arrangement incidental to two specific applications thereof, it is to be understood that the invention is limited neither to the mere details or relative arrangement of parts, nor to its specific embodiments shown herein, but that extensive deviations from the illustrated forms or embodiments of the invention may be made, without departing from the principles thereof.

What I claim is:

1. A table or the like having an opening in the top thereof through which a lamp cord may pass, and a removable plug for such opening, forming a closure therefor, the plug being formed with means for limiting upward movement of such plug, the upper surface of the plug when in inserted position being planar with the upper surface of the table top, and retaining means for the plug comprising a block pivotally mounted on the lower surface of the table top, the block being swingable to one side of the opening to permit the plug to be removed.

2. A table or the like having an opening in the top thereof through which a lamp cord may pass, and a removable plug for such opening, forming a closure therefor, such opening having an enlarged portion at its lower end forming a shoulder, the plug being formed with a flange at its lower end providing a collar which abuts against the shoulder, limiting upward movement of such plug, the upper surface of the plug when in inserted position being substantially planar with the upper surface of the table top, and means for

supporting the plug when in such inserted position comprising a block pivotally mounted on the lower surface of the table top, and means for supporting the plug when it is removed from the opening.

3. A table or the like having an opening in the top thereof through which a lamp cord may pass, and a removable plug for such opening, forming a closure therefor, such opening having an enlarged portion at its lower end forming a shoulder, the plug being formed with an annular flange at its lower end providing a collar which abuts against the shoulder, limiting upward movement of such plug, the upper surface of the plug when in inserted position being planar with the upper surface of the table top and fitting snugly within the opening to provide a smooth, unbroken upper surface for such table top, means for supporting the plug when in such inserted position comprising a block pivotally mounted on the lower surface of the table top, and means for supporting the plug when it is removed from the opening comprising a horizontal recess in the block which receives the plug, the recess having an enlarged portion which supports the annular flange.

4. A table or the like having an opening in the top thereof through which a lamp cord may pass, and a removable plug for such opening, forming a closure therefor, such opening having an enlarged portion at its lower end forming a shoulder, the plug being formed with a flange at its lower end providing a collar which abuts against the shoulder, limiting upward movement of such plug, and means for supporting the plug when in inserted position within the opening comprising a block pivotally mounted on the lower surface of the table top, the block having a vertical aperture which registers with the table top opening when such block is rotated to a predetermined position, thus permitting the plug to drop into said aperture, and a lower wall for the aperture forming a support for the plug, said aperture being of such dimensions as to receive the entire plug and permit it to rest below the table top.

5. A table or the like having an opening in the top thereof through which a lamp cord may pass, and a removable plug for such opening, forming a closure therefor, such opening having an enlarged portion at its lower end forming a shoulder, the plug being formed with a flange at its lower end providing a collar which abuts against the shoulder, limiting upward movement of such plug, the upper surface of the plug when in inserted position being planar with the upper surface of the table top and fitting snugly within the opening to provide a smooth, unbroken upper surface for such table top, means for supporting the plug when in such inserted position comprising a block pivotally mounted on the lower surface of the table top, and means for supporting the plug when it is removed from the opening, the block having an aperture extending downwardly from its upper surface and terminating above its lower surface, the plug being adapted to drop into said aperture when the block is revolved to a point wherein such aperture registers with the opening in the table top, thus permitting the plug to drop into said aperture, and a lower wall for the aperture forming a support for the plug said aperture being of such dimensions as to receive the entire plug and permit it to rest below the table top.

SYLVIA D. EPWORTH.
